UNITED STATES PATENT OFFICE.

OTTO JAEGER, OF ELKINS PARK, PENNSYLVANIA, ASSIGNOR TO HARRY S. KELSEY, OF BOSTON, MASSACHUSETTS.

VENDING-MACHINE.

1,322,307.

Specification of Letters Patent.

Patented Nov. 18, 1919.

Original application filed September 22, 1917, Serial No 192,666. Divided and this application filed December 17, 1918. Serial No. 267,100.

To all whom it may concern:

Be it known that I, OTTO JAEGER, a citizen of the United States, residing at Elkins Park, county of Montgomery, State of Pennsylvania, have invented certain new and useful Improvements in Vending-Machines, of which the following is a full, clear, and exact description, reference being had to the accompanying drawings, forming

10 a part of this specification.

My invention relates to improvements in vending machines particularly adapted to vend coffee and other liquid commodities, and is a division of my co-pending application, Serial No. 192,666, filed September 22, 1917.

The object of my invention is to provide a novel, simple and efficient dispensing mechanism including a discharge opening for 20 the commodity to be vended, and also to provide a coin or check controlled mechanism for operating the dispensing mechanism and related thereto in such manner that a coin or check inserted into the machine will be prevented from operating the dispensing mechanism until a suitable receiver shall have been placed beneath the discharge opening to receive the said commodity.

30 With the above and related objects in view, my invention consists of the elements and combinations of them hereinafter described and claimed.

In the accompanying drawings, illustrating my invention:

Figure 1 is a front elevation, partly broken away, of a vending machine embodying my invention.

Fig. 2 is a side elevation thereof.

40 Fig. 3 is a vertical section through the liquid dispensing vessels and adjuncts, on line 3—3 of Fig. 1.

Fig. 4 is a horizontal section, on line 4—4 of Fig. 3, showing the support for the receiving cup and adjuncts.

45 Figs. 5 and 6 are enlarged front views of a portion of the valve operating mechanism showing the parts in different positions.

50 Fig. 7 is a horizontal section on line 7—7 of Fig. 6.

Fig. 8 is a sectional detail, on line 8—8 of Fig. 7.

Fig. 9 is a section on line 9—9 of Fig. 2, showing the speed governor.

55

Fig. 10 is a sectional detail of the speed governor, on line 10—10 of Fig. 9.

Fig. 11 is a section on line 11—11 of Fig. 2, showing the coin controlled parts and adjuncts.

60

Figs. 12 and 13 are sectional and detail views showing the coin controlled parts.

Fig. 14 is a sectional plan of the coin controlled parts, on line 14—14 of Fig. 12.

65

The frame structure of the machine comprises base bars 2, standards 4, secured to and rising from the bars 2, and bars 5 connecting the standards 4.

Supported on horizontal bars 13, which are secured to and project from the standards 4 are two storage vessels 14 and 15 adapted to contain certain commodities, such as cream and coffee, respectively.

70

The bottoms of the vessels 14 and 15 are provided with downwardly extending measuring vessels 16 and 17 which inclose measuring chambers 18 and 19, respectively. Disposed within the chambers 18 and 19 are vertically movable valve members 20 and 21 having valves 22 and 23 formed on their upper ends and valves 24 and 25 formed on their lower ends respectively. The valves 22 and 23 are adapted to seat against the walls of passages 26 and 27 formed on the tops of the measuring vessels 16 and 17 to afford communication between the storage vessels 14 and 15 and the measuring chambers 18 and 19, respectively; and the valves 24 and 25 are adapted to seat against the walls of passages 28 and 29 formed in the bottoms of the vessels 16 and 17, respectively, to permit the contents of the chambers 18 and 19 to be discharged therefrom.

75

By mechanism hereinafter described, the valve members 20 and 21 are adapted to be quickly raised and thereafter quickly lowered to discharge the contents of the chambers 18 and 19 and to permit them to be refilled from the vessels 14 and 15.

80

When the valve members 20 and 21 are lowered to the normal position, shown by full lines in Fig. 3, the valves 24 and 25 are closed and rest upon their seats and the valves 22 and 23 are open. In this normal position of the parts, cream and coffee pass from the vessels 14 and

100

105

15 through the passages 26 and 27 and fill the measuring chambers 18 and 19. When the valve members 20 and 21 are quickly raised from the normal position to 5 the dotted line position, the valves 22 and 23 are closed and the valves 24 and 25 are opened. In this dotted line position of the parts, the measured cream and coffee contained within the chambers 18 and 19 are 10 permitted to flow therefrom through the passages 28 and 29, while the valves 22 and 23 prevent cream and coffee from entering the chambers 18 and 19 from the vessels 14 and 15. After the cream and coffee have 15 been discharged from the chambers 18 and 19, the valve members 20 and 21 are quickly lowered to the full line or normal position to permit the measuring chambers 18 and 19 to be again filled from the vessels 14 and 20 15 for a succeeding operation. It will thus be seen that measured quantities of cream and coffee may be successively discharged by raising and lowering the valve members 20 and 21.

25 When the cream and coffee are thus discharged from the receiving chambers 18 and 19 they are received within a trough 30 supported beneath the measuring vessels 16 and 17. The trough 30 has a discharge spout 31 and an inclined bottom leading to the spout 31, so that the cream and coffee entering the trough 30 will flow therefrom through the spout 31. Located beneath the spout 31 is a floor or shelf 32 to receive and support a 35 cup 33 beneath the spout 31 so that the cup 33 may receive the mixed cream and coffee which flows from the spout 31.

I shall now describe the mechanism for raising and lowering the valve members 20 40 and 21 for the discharge of the measured quantities of cream and coffee.

The upper ends of the valve members 20 and 21 are connected to the lower ends of the chains 34, and the upper ends of the 45 chains 34 are connected to arms 35 projecting from a rockable shaft 36 which is mounted to turn in brackets 37 on the machine frame. The arms 35 are adapted to turn on the shaft 36 under certain conditions and to turn with the shaft 36 under certain other conditions, for purposes hereinafter explained, and, therefore, I provide each arm 35 with a shoulder 37' and I provide the shaft 36 with pins 38 adapted to 50 engage the shoulders 37' to turn the arms 35 with the shaft 36 when it is turned in one direction, indicated by the arrow in Fig. 5, and to permit the shaft 36 to be turned in the reverse direction independently of the 55 arms 35. Adjacent to the arms 35 are arms 39 which are secured to the shaft 36 and have beveled or inclined free ends 40. The adjacent free ends of the arms 35 are also beveled or inclined at 41, oppositely to the

ends of the arms 39, as clearly shown in 65 Figs. 5 and 6; and the beveled ends of the arms 39 are adapted to be engaged by the lower ends of links 42 which have their upper ends pivoted, as at 43, to a bar 44 which connects the bearing brackets 37. The location of the link pivots 43 with relation to the ends 40 and 41 of the arms 35 and 39 is such that the lower ends of the links 42 always rest against one or the other of the arms 35 and 39 and tend to move with gravity toward the shaft 36, for a purpose presently appearing. Secured to the respective ends of the shaft 36 are two arms 45 and 46 provided with a roller 47 and a weight 48, respectively. The weighted arm 46 tends to hold the roller 47 in engagement with a cam wheel 49 and tends to turn the shaft 36 in a direction to raise the arms 35 and 39, the shoulders 37' of the arms 35 resting normally against the pins 38.

The cam wheel 49 is secured to a shaft 50 which is mounted to turn in suitable bearings on the machine frame; and the wheel 49 is provided with spaced, projecting cam teeth 51 having inclined faces 52 and formed 90 as shown in the drawings.

The cam wheel 49 controls the valve members 20 and 21, and in the normal position of the parts, one of the teeth 51 is in registry with the roller 47 and the roller 47 rests 95 against the outer face of the tooth. When it is desired to move the valve members 20 and 21 to discharge the contents of the chambers 18 and 19, the wheel 49 is turned in the direction of the arrow to bring the next succeeding tooth 51 into registry with the roller 47, and the following operation takes place: Immediately after the wheel 49 starts to turn, the tooth 51 engaging the roller 47 escapes the same, permitting the weighted arm 46 and roller 47 to drop, thereby permitting the weighted arm 46 to turn the shaft 36 and raise the arms 35 and 39 and cause the arms 35 and chains 34 to quickly raise the valve members 20 and 100 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940

from the chambers 18 and 19. As the said next succeeding tooth 51 comes into registry with the roller 47, the inclined face 52 of the tooth raises the roller 47, and the wheel 49 is stopped with the roller 47 resting against the outer face of the tooth 51. When the inclined face 52 of the tooth 51 raises the roller 47, as just described, it moves the arm 45 to turn the shaft 36 and thereby raise the weighted arm 46 and lower the arms 39 from the position shown in Fig. 6 to the position shown in Fig. 5. As the arms 39 are thus lowered, the links 42 hold the arms 35 in the position shown in Fig. 6, and thereby hold the valves 22 and 23 closed, while the pins 38 move away from the shoulders 37'; and, just before the arms 39 reach the position shown in Fig. 5, the beveled ends thereof engage the links 42 and move them outwardly from beneath the ends of the arms 35, freeing them and permitting them and the valve members 20 and 21 to drop instantly to the position shown in Figs. 3 and 5 and thereby quickly close the valves 24 and 25 and open the valves 22 and 23, leaving the parts in the position shown in Figs. 3 and 5 for a succeeding operation. It will thus be seen that each time the wheel 49 is turned to move a tooth 51 from the roller 47 and bring the next tooth 51 into registry therewith, the liquid chambers 18 and 19 will be discharged and refilled.

I shall now describe the means for turning the wheel 49. The shaft 50 is provided with a pinion 53 in mesh with a gear wheel 54 on a shaft 55 which is journaled in suitable bearings on the machine frame. The shaft 55 carries a pinion 56 which is in mesh with a gear wheel 57 on a shaft 58 which turns in bearings on the upper portion of the machine frame. The shaft 58 is provided with a pair of sprocket wheels 59 over which the upper ends of a pair of vertically-disposed sprocket chains 60 pass and with which they are engaged. The lower ends of the chains 60 pass beneath and are engaged with a pair of sprocket wheels 61 on a shaft 62 which extends parallel to the shaft 58 and turns in bearings on the lower portion of the machine frame. The sprocket chains 60 carry a weight 63 which extends between opposite sides thereof and which is secured thereto. The weight 63 tends to turn the sprocket wheels 59 and shaft 58 in the direction of the arrow in Fig. 1, thereby tending, through the gear wheels 57 and 54 and the pinions 56 and 53 to turn the shaft 50 and cam wheel 49 in the direction of the arrow, for the purpose hereinbefore described.

The turning of the cam wheel 49 by the weight 63 is governed by a controlling shaft 64 which turns in bearings on the machine frame and which is connected to the shaft 50 of the cam wheel 49 by a sprocket chain 65 which passes around and is engaged with sprocket wheels 66 and 67 on the shafts 50 and 64 respectively, and which also passes around and is engaged with a sprocket wheel 68 on a shaft 69 which turns in a bracket 70 on the machine frame and which will be referred to later.

The power of the weight 63, in tending to turn the cam wheel 49 in the direction of the arrow, also tends to turn the controlling shaft 64 in the direction of the arrow, and the shaft 64 is normally prevented from being thus turned by a ratchet wheel 71 having laterally extending teeth 72, and by a member 73 having an arm 74 which is engaged with one of the ratchet teeth 72. The member 73 is pivoted at 75, to a bracket 76 on the machine frame, and the arm 74 of the member 73 is pivoted thereto and held normally against a stop wall 76' thereon by the action of a spring 77, one end of which is attached to the member 73 and the other end of which is attached to the arm 74. The purpose of pivoting the arm 74 to the member 73 will be hereinafter described. Normally, the arm 74 is engaged by a ratchet tooth 72, and is held against the stop wall 76' and thereby prevents the turning of the shaft 64 by the weight 63, and the location of the pivot 75 of the member 73 with relation to the point of engagement of the arm 74 with the ratchet tooth 72 is such that the pressure of the tooth 72 against the arm 74 tends to move the arm 74 and member 73 from the position shown in Fig. 12 to the position shown by full lines in Fig. 13 to thereby release the ratchet wheel 71 from the arm 74 and permit the controlling shaft 64 and the cam wheel 49 to be turned by the weight 63, and thereafter permit the member 73 to return by gravity to the position shown in Fig. 12. The member 73 is held normally in the position shown in Fig. 12 by certain devices which will be presently described, and which are operative to release the member 73 and to reengage the same and again hold it in the position shown in Fig. 12, when it returns thereto by gravity. When the member 73 is released, the weight 63 is thereby permitted to turn the ratchet wheel 71, which, acting against the arm 74, moves the member 73 to the position shown by full lines in Fig. 13, whereupon the ratchet tooth 72 engaged with the arm 74 escapes the same, and, thereafter, the end of the arm 74 bears against the side of the ratchet tooth 72, as the member 73 tends by gravity to resume the position shown in Fig. 12. The sides of the teeth 72 are beveled or inclined, as shown to permit the arm 74 and member 73 to return to the position shown in Fig. 12, after the member 73 is operated to release each ratchet tooth 72 and before the next succeeding tooth 72 reaches

- the arm 74 to engage the same and prevent the further turning of the controlling shaft 64 and also the further turning of the cam wheel 49. The gearing between the controlling shaft 64 and the cam wheel 49 is such that each time the member 73 is operated to release the ratchet wheel 71 and permit it to turn a distance equal to the distance between two of its teeth 72, as just described, 10 the weight 63 will be permitted to turn the cam wheel 49 a distance equal to the distance between two of its teeth 51, for a liquid dispensing operation, as hereinbefore described.
- 15 To prevent the weight 63 from turning the cam wheel 49 too rapidly during each dispensing operation, I provide a retarding means or governor, as follows: The shaft 69, hereinbefore referred to, has a ratchet wheel 78 secured thereon which engages a pawl 79 carried by a gear wheel 80 which is loosely mounted on the shaft 69, the pawl 79 being pressed against the ratchet wheel 78 by a spring 81 carried by the wheel 80. 20 The ratchet wheel 78 causes the gear wheel 80 to turn with the shaft when the shaft 69 is turned in the direction of the arrow under the influence of the weight 63; and the pawl 79 permits the shaft 69 to be turned in the 25 reverse direction independently of the wheel 80, for the purpose hereinafter explained. The gear wheel 80 is in mesh with a pinion 82 on a shaft 83 which turns in the bracket 70 and which carries a gear wheel 84. The 30 gear wheel 84 is in mesh with a pinion 85 on a shaft 86 which turns in the bracket 70 and which has an outwardly projecting end carrying a fan 87, the rotation of which is resisted by the surrounding air. It will thus 35 be seen that the fan 87 and the gearing between it and the sprocket wheel 68 will regulate and control the speed at which the weight 63 is permitted to turn the cam wheel 49.
- 40 The member 73 hereinbefore referred to is preferably controlled and operated by proper checks or coins inserted into the machine for the purpose of operating the liquid dispensing devices, and I shall now describe 45 the coin operated devices for this purpose.

Formed in a wall 88 on the frame structure of the machine, adjacent to the shelf or support 32 for the cup 33 is a slot 89 for the reception of the check or coin 90 which is to 50 operate the machine; and supported by the bracket 76 is a receiver 91 which receives the coin 90 from the slot 89 and comprises an upper portion 92 which is inclined downwardly from a position below the slot 89, and a 55 lower vertical portion 93 which extends downwardly from the lower end of the inclined portion 92 and forms a continuation thereof. This receiver 91 forms a guideway adapted to maintain the opposite faces of

the coin 90 in vertical position and to permit 65 the coin to roll down through the inclined portion 92 and thereafter to descend by gravity through and fall from the lower end of the vertical portion 93.

Fulcrumed, at 94, on a bracket on the 70 wall 88 is a lever 95 having an arm 96 which extends away from the wall 88 and having an arm 97 which extends to a position immediately back of one end portion of the slot 89. The end wall of the 75 slot 89 opposite to the free end of the lever arm 97 is located with respect to said free end so that when a coin 90 of the proper dimensions is inserted into the slot 89, the 80 coin 90 will engage the free end of the lever arm 97 and the opposing end wall of the slot 89 and move the lever 95 from the position shown in Fig. 12 to the position shown in Fig. 13, whereupon the coin 90 will escape 85 the lever arm 97 and fall therefrom by gravity. The lever arm 96 is connected by a link 98 to an arm 99 which is pivoted, at 100, to the bracket 76 and which is adapted to be raised by the lever 95 from the position shown in Fig. 12 to the position 90 shown in Fig. 13, when the coin 90 is inserted into the slot 89. Resting normally upon the arm 99 is the free end of an arm 101 which is pivoted, at 102, to an extension 95 on the bracket 76 and which is adapted to be raised from the position shown in Fig. 12 to the position shown in Fig. 13, when the arm 99 is raised as just described. The 100 arm 101 is provided with a lateral projection 103 which is adapted to be engaged by the upper end of the member 73 and prevent the movement thereof by the ratchet wheel 71, as previously described, when the arm 101 is in the normal position shown in Fig. 12. When the arm 101 is raised to the position shown in Fig. 13, the projection 103 escapes the upper end of the member 73 105 and releases the same.

When member 73 is thus released by the projection 103 the pressure of the ratchet 110 wheel 71 against the arm 74 moves the member 73 from the position shown in Fig. 12 to the position shown by dotted lines in Fig. 13, and the projection 103 rests upon the member 73 and supports the arm 101 115 in a position midway between the positions shown in Figs. 12 and 13, while the lever arm 95 and the arm 99 drop back to the position shown in Fig. 12, independently of the arm 101. The member 73 reaches the 120 position shown by dotted lines in Fig. 13 before the arm 74 escapes the tooth 72 of the ratchet wheel 71 with which it is engaged, and the further movement of the member 73 is prevented by a pin 104 which is engaged 125 by a tooth 105 on an arm 106 which projects from the member 73. The pin 104 is carried by one arm 107 on a balanced lever

108 which is fulcrumed, at 109, on a projection on the coin receiver 91, the other arm 110 of which is weighted to maintain the lever 108 normally in the position shown 5 in Fig. 12.

The pin 104 projects through the coin path in the lower end of the vertical portion 93 of the coin guide 91, so that a coin 90 descending through the portion 93 will 10 strike the pin 104 and thereby move the pin downwardly from the tooth 105 as the coin 90 escapes from the bottom of the coin guide 91. When the tooth 105 is thus released, the pressure of the ratchet wheel 71 moves the 15 member 73 to the position shown by full lines in Fig. 13 and the ratchet tooth 72 engaged with the arm 74 escapes the same and permits the ratchet wheel 71 to turn under the influence of the weight 63 as previously 20 described. This done, the end of the arm 74 bears against the side of the ratchet tooth 72, and the member 73 tends to return by gravity to the position shown in Fig. 12, while the pin 104 rests against the inclined 25 bottom of the tooth 105 as the lever 110 tends to return it to its normal position shown in Fig. 12. When the side of the ratchet tooth 72 escapes the end of the arm 74, the member 73 returns by gravity to the normal position 30 shown in Fig. 12. When the member 73 thus returns to the normal position, the pin 104 escapes from engagement with the bottom of the tooth 105 and returns to its normal position shown in Fig. 12, and the upper 35 end of the member 73 moves from beneath the projection 103 and permits the arm 101 to fall by gravity to its normal position shown in Fig. 12 and again lock the member 73 against movement by the ratchet 40 wheel 71, before the next succeeding ratchet tooth 72 reaches the arm 74 so that when the said next succeeding tooth 72 reaches and engages the arm 74, it will stop further movement of the ratchet wheel 71 and controlling 45 shaft 64 until the member 73 is again released from the arms 101 and 107 by the insertion of another coin 90 into the slot 89. It will thus be seen that each time a coin 50 passes through the coin guide 91, a mixed quantity of cream and coffee will be discharged into the cup 33 placed upon the support 32 to receive it.

In order to prevent the discharge of coffee from the spout 31 before a cup has been 55 placed upon the shelf 32 to receive it, I provide the following: Extending rearwardly from the position occupied by a cup 33 when placed upon the shelf 32 is a rod 111 which is mounted to slide in a wall 112, rising from 60 the back of the shelf 32, and in a bracket 113 secured to the back of the wall 112. The forward end of the rod 111 is provided with an abutment plate 114 adapted to be engaged by a cup 33; and the rod 111 is held

normally in the full line position shown in Fig. 3 by a spring 115 one end of which is attached to the wall 112 and the other end of which is attached to a pin extending from the rod 111. When a cup 33 is placed upon the shelf 32 beneath the spout 31 in the position shown by dotted lines in Fig. 3, the rod 111 is thereby pushed back against the action of the spring 115 to the position shown by dotted lines; and when the cup 33 is moved from the shelf 32, the spring 115 returns the rod 111 to the normal or full line position.

Connected to the rod 111 is one arm 116 of a lever 117 which is fulcrumed, at 118, on a bracket 119 projecting from the wall 112. The lever arm 116 extends through a slot in the rod 111 so that when the rod 111 is moved from the full line to the dotted line positions shown in Figs. 3 and 4, the lever 117 will be correspondingly moved. The arm 120 of the lever 117 has a cam portion 121 adapted to engage an arm 122 which is pivoted at its lower end to the bracket 119. The upper end of the arm 122 extends to and rests normally against one side of the inclined portion 92 of the coin guide 91, and the upper end of the arm 122 is provided with a pin 123 which extends into the coin path of the inclined portion 92 of the coin guide 91. When the lever 117 is moved to the dotted line position shown in Fig. 4, the cam 121 acts against the arm 122 and moves the upper end thereof away from the coin guide 91 and withdraws the pin 123 therefrom; and when the lever 117 is moved to the full line position, the arm 122 returns by gravity to its normal position, resting against the coin guide 91, and the pin 123 is returned to its normal position in the coin path. When the pin 123 is in the coin path, it operates to arrest the movement of a coin 90 rolling down the inclined portion 92 of the guide 91 and prevents the coin 90 from reaching the vertical portion 93 of the guide. When, however, the pin 123 is withdrawn from the coin path, the arrested coin 90 will be liberated and will roll to and descend through the vertical portion 93 of the guide 91 and operate the lever 108 to release the member 73 for the discharge of a cup of coffee from the spout 31, as previously explained.

From the construction just described, it will be understood that if a cup 33 be placed upon the shelf 32 in the position shown in Fig. 3, before a coin is inserted into the slot 89, the cup 33 will engage the plate 114 and push the rod 111 back to the position shown by dotted lines, thereby moving the lever 117 to the position shown by dotted lines in Fig. 4, and causing the cam 121 to operate the arm 122 to withdraw the pin 123 from the coin path of the coin guide 91. There-

fore, when the coin 90 is inserted into the slot 89 it will be free to pass through the inclined portion 92 and vertical portion 93 of the coin guide 91 and the machine will be 5 operated, as previously described, to discharge a cup of coffee from the spout 31. If, however, the coin 90 is inserted into the slot 89 before a cup has been placed beneath the spout 31, the pin 123 will arrest the 10 downward movement of the coin 90 through the coin guide 91 and prevent the coin from operating the coffee discharging devices, until a cup is placed beneath the spout 31, whereupon the arrested coin will be released 15 and will then operate the coffee discharging devices as previously explained.

To raise the weight 63 after it has been lowered in operating the machine, I provide the controlling shaft 64 with an outwardly 20 extending square end 125 for the reception of a suitable hand crank by means of which the shaft 64 may be turned. When it is desired to raise the weight 63, the crank is applied to the shaft 64 and it is turned in the 25 direction of the dotted line arrow in Fig. 1, while the arm 45 and roller 47 are held raised by hand to maintain them out of engagement with the cam wheel 49. This turning of the shaft 64 operates the gearing between it and the chains 60 to raise the weight 63; and, during this operation, the pivoted arm 74 of the member 73 springs 30 past the teeth 72 of the ratchet wheel 71 without moving the member 73, and the pawl 79 permits the sprocket wheel 68 to turn independently of the gearing between it and the cam 87 which controls the speed of the downward movement of the weight 63 when it operates the machine.

40 I claim:

1. In a vending machine, the combination of a receiver for the commodity to be vend- 45 ed, said receiver having an opening therein for the discharge of the commodity, a gravity element adapted to descend when released, means for supporting and guiding said element, a member normally preventing the descent of the gravity element, an abutment adjacent to said opening adapted to be 50 engaged and moved from a normal position by a receptacle placed beneath said opening to receive the commodity, means operated by said abutment when moved from its normal position to operate said member to release the gravity element, and mechanism operative, by the descent of the gravity element when released, to effect a discharge of the commodity through said opening.

2. In a vending machine, the combination 65 of a receiver for the commodity to be vend- ed, said receiver having an opening therein for the discharge of the commodity, a gravity element adapted to descend when released, means for supporting and guiding

said element, a member normally preventing 65 the descent of the gravity element, an abutment adjacent to said opening to be engaged and moved from a normal position by a receptacle placed beneath said opening to receive the commodity, means operated by said 70 abutment when moved from its normal position to operate said member to release the gravity element, and mechanism operative, by the descent of the gravity element when released, to effect a discharge of the commodity through said opening, said member and said abutment automatically returning to their normal positions when moved therefrom and released.

3. In a vending machine, the combination 80 of a receiver for the commodity to be vend- ed, said receiver having an opening therein for the discharge of the commodity, a gravity element adapted to descend when released, means for supporting and guiding said element, a member normally preventing the descent of the gravity element, a recipro- 85 cative abutment adjacent to said opening to be engaged and moved from a normal position by a receptacle placed beneath said 90 opening to receive the commodity, a spring to return said abutment to said normal position after being moved therefrom and released, a lever operated by said abutment when moved from said normal position, said lever, when operated, moving said member from its normal position and thereby releasing the gravity element, and mechanism operative, by the descent of the gravity element when released, to effect a discharge of the commodity through said opening.

4. In a vending machine, the combination 95 of a receiver for the commodity to be vend- ed, said receiver having an opening therein for the discharge of the commodity, a gravity element adapted to descend when released, means for supporting and guiding said element, a pivoted member normally preventing the descent of the gravity element, a recipro- 100 cative abutment adjacent to said opening to be engaged and moved from a normal position by a receptacle placed beneath said opening to receive the commodity, a spring to return said abutment to said normal position after being moved therefrom and released, a lever operated by said abutment when moved from said 110 normal position, said lever, when operated, moving said member from its normal position and thereby releasing the gravity element, and mechanism operative, by the descent of the gravity element when released, to effect a discharge of the commodity through said opening.

5. In a vending machine, the combination 115 of a receiver and discharge means for the commodity to be vended, means for controlling the discharge of said commodity

comprising means normally urging the operation of said discharge means, means normally restraining said normally urged means, a movable control element, means 5 for guiding the passage of said control element from one position to another, a plurality of members disposed in the path of and successively engageable by said movable control element in its movement from 10 one position to another, said members operative, when actuated by said control element, to release said restraining means from said normally urged means.

6. In a vending machine, the combination of a receiver having a discharge opening for the commodity to be vended, movable means for opening and closing said discharge opening, means connected to said movable means and normally urging the 15 movement thereof to open said discharge opening, means normally restraining said urging means, said restraining means comprising a pendulous member operative to move from its inactive position under the 20 influence of said urging means to an ante-releasing position, means normally locking said pendulous member in its normally inactive position, a traveling element, means connected to said locking means and en- 25 gageable by said traveling element for unlocking said pendulous member, whereby the latter is moved to its ante-releasing position, means normally obstructing further movement of said pendulous member, said 30 obstructing means operative upon engagement by said traveling element to relieve said pendulous member from said obstructing means, means located intermediate of said unlocking means and said obstructing 35 means for normally impeding the movement of said traveling element from the former to the latter, movable receptacle engaging means connected to said impeding means and operative upon the placing of a recep- 40 tacle adjacent said discharge opening to move said impeding means out of the path of said traveling element whereby the latter engages the obstructing means, said pendulous member operative upon relief of 45 said obstructing means to move to releasing position whereby said urging means is free to operate said movable means for said opening for discharge of said commodity to said receptacle, and means for automatically restoring the parts to initial inactive 50 positions.

7. In a vending machine provided with a receiver and a discharge means for the commodity to be vended, the combination of 55 means for controlling said discharge means comprising a weight actuated escapement means abnormally operative to operate said discharge means, a pendulous member in normal restraining engagement with said es-

capement means, said escapement means 65 normally urging said pendulous member toward mutual disengagement, means for normally locking said pendulous member in inactive position, independent means connected with said pendulous member for obstructing complete mutual disengagement of said escapement means and said pendulous member after operation of said locking means, a gravity actuated traveling element, means connected with said locking means 70 operative upon engagement by said traveling element to first unlock said pendulous member, said pendulous member operative to move through a predetermined distance, impeding means located in the path of said traveling element between said locking means and said obstructing means for normally impeding further movement of said traveling element toward said obstructing means, receptacle engaging means connected 75 to said impeding means and operative upon engagement by a receptacle placed adjacent said discharge means to move said impeding means out of the path of said traveling element, said obstructing means 80 operative upon engagement by said traveling element to relieve said pendulous member for further movement whereby the same is disengaged from said escapement means and the discharge means operated, and 85 means for automatically restoring the parts to the initial inactive positions.

8. In a bending machine provided with a receiver and a discharge means for the commodity to be vended, the combination of 100 means for controlling said discharge means comprising a weight actuated escapement means abnormally operative to operate said discharge means, a pendulous member in normal restraining engagement with 105 said escapement means said escapement means normally urging said pendulous member toward mutual disengagement, means for normally locking said pendulous member in inactive position, independent 110 means connected with said pendulous member for obstructing complete mutual disengagement of said escapement means and said pendulous member after operation of said locking means, a gravity actuated trav- 115 eling element, means for supporting and guiding said traveling element, means connected with said locking means operative upon engagement of said traveling element to first unlock said pendulous member, said pendulous member operative to move through a predetermined distance, impeding means projecting within said guiding means intermediate of the ends thereof in the path of said traveling element for normally im- 120 peding further movement of said traveling element toward said obstructing means, said obstructing means located at the other end 125

- of said guiding means, receptacle engaging means connected to said impeding means and operative upon engagement by a receptacle placed adjacent said discharge means 5 to move said impeding means out of the path of said traveling element, said obstructing means operative upon engagement by said traveling element to relieve said pendulous member for further movement 10 whereby the same is disengaged from said escapement means and the discharge means operated, and means for automatically restoring the parts to the initial inactive positions.
- 15 9. In a vending machine, the combination of a receiver and discharge means for the commodity to be vended, means for controlling the discharge of said commodity comprising weight actuated means normally 20 urging the operation of said discharge means, movable means normally restraining said normally urged means, means for locking said movable means in normal inactive position, a movable control element, means for 25 guiding the passage of said control element from one position to another, a plurality of members disposed in the path of and successively engageable by said movable control element in its movement from one position to another, one of said members operative 30 upon engagement of said control element to release the locking means from said movable means, the other members operative upon subsequent engagement of said control 35 element to release said movable means from said weight actuated means, and a third member intermediate the other said members for impeding the movement of said control element and means to remove the same 40 out of the path of said control element.
10. In a vending machine, the combination of a receiver having a discharge opening for the commodity to be vended, movable means for opening and closing said discharge opening, weight actuated means comprising an escapement wheel connected to said movable means and normally urging the movement thereof to open said discharge opening, means normally restraining the 45 movement of said escapement wheel and said urging means, said restraining means comprising a pendulous member operative to move from its inactive position under the influence of said urging means to an ante-releasing position, means normally locking said pendulous member in its normally inactive position, a traveling element, means for guiding the passage of said traveling element, means connected to said locking 50 means projecting within the guiding means near one end thereof and engageable by said traveling element for unlocking said pendulous member, whereby the latter is moved to its ante-releasing position, means at the 55 other end of said guiding means for normally obstructing further movement of said pendulous member, said obstructing means operative upon engagement by said traveling element to relieve said pendulous member from said obstructing means whereby 60 said pendulous member is moved for complete disengagement with said escapement wheel, means projecting within said guiding means and located intermediate said unlocking means and said obstructing means for normally impeding the movement of said traveling element from the former to the latter, movable receptacle engaging means connected to said impeding means and operative upon the placing of a receptacle adjacent said discharge opening to move said impeding means out of the path of said traveling element whereby the latter engages the obstructing means, said pendulous member operative upon relief of said obstructing 65 means to move to releasing position whereby said urging means is free to operate said movable means for said opening for discharge of said commodity to said receptacle, and means for automatically restoring the 70 parts to the initial inactive positions.
11. In a vending machine, the combination of a receiver and discharge means for the substance to be vended, means normally tending to automatically operate said discharge means, a movable means normally restraining operation of said second-mentioned means, means for normally retaining said movable restraining means in inactive position, a movable control element, said retaining means operative upon initial movement of said control element to release said movable restraining means for movement through a predetermined distance, means for impeding further movement of said control element, means for obstructing further movement of said restraining means, means operative upon the placing of a receptacle adjacent said discharge means for rendering said impeding means ineffective whereby 75 further movement of said control element is permitted, said obstructing means operative upon said further movement of said control element to release said restraining means for further movement whereby the latter is disengaged from said second-mentioned means and the discharge means operated, and means for automatically restoring the said 80 means to initial inactive positions.
12. In a vending machine, the combination of a receiver for the commodity to be vended, a discharge means therefor, means for controlling said discharging means, said means including a gravity element adapted to descend when released, means for normally restraining the descent thereof, a reciprocating means operatively connected to said restraining means, yielding means 85

normally maintaining said reciprocating means inactive, said reciprocating means operative when engaged by a receptacle placed beneath said discharge means for 5 withdrawing said restraining means from said gravity element whereby the latter is permitted to descend, a counter weighted member normally retaining said control means inactive, said counter weighted member operative when engaged by said descend-
10

ing gravity element to release said control means.

In testimony whereof I have hereunto affixed my signature this 16th day of December, A. D. 1918.

OTTO JAEGER.
